UNITED STATES PATENT OFFICE.

PHILIPP MENGES, OF NEW YORK, N. Y.

GAS-BURNER.

SPECIFICATION forming part of Letters Patent No. 377,494, dated February 7, 1888.

Application filed May 16, 1887. Serial No. 238,310. (No model.)

To all whom it may concern:

Be it known that I, PHILIPP MENGES, of the city of New York, county and State of New York, have invented a new and Improved 5 Gas-Burner, of which the following is a specification.

This invention relates to a gas-burner which is so constructed that when the flame is accidentally extinguished the cock controlling the 10 supply of gas will be automatically turned off, thus checking the further supply of gas.

The invention consists in the various features of improvement, more fully pointed out in the claims.

15 The following is a full and clear description of my invention, reference being had to the accompanying drawings, in which—

Figure 1 is a side view of my improved gas-burner with the gas turned on, but before the 20 gas is lighted. Fig. 2 is a similar view with the gas lighted and the rods expanded. Fig. 3 is a detail view showing the position of the disk and pawl after the gas has been turned off. Fig. 4 is a detail view of the pawl. Fig. 5 25 shows a modification of the disk *i*. Fig. 6 shows a modification in the number of rods *e* of the burner.

The letter *a* represents the nozzle in which the gas-supply pipe is screwed and leading to 30 burner *b*, controlled by cock *c*, as usual.

d is a bracket surrounding burner *b* and carrying two (more or less) rods, *e*, of brass or other expandible metal. Figs. 1 and 2 show the employment of two rods, *e*. One rod is 35 rigidly connected at one end to one arm of bracket *d*, while its other or free end is connected to a link, *f*, pivoted to the other arm of the bracket. This link is also connected to one end of the second rod *e*, while the other 40 end of such rod is connected to the gas-controlling device hereinafter described.

In Fig. 6 I have shown three rods, *e*, connected by two links, *f*, and thus any number of connecting-rods may be used. The advantage of 45 multiplying the number of rods *e* and connecting them by pivoted links is that the expansion of one rod will be transmitted to and cause a motion of the next rod, and thus the motion of the free end of the uppermost or 50 working rod will be greatly multiplied. In this way the motion imparted to the gas-controlling devices is increased and more positive,

which is of importance, as I have found that the expansion or contraction of but a single rod is not sufficient to cause a perfect or reliable working of the parts. 55

The free end of the working-rod *e* is attached to a lever, *g*, which in turn engages a second lever, *h*, to which there is pivoted a pawl, *j*, held against a disk, *i*, having nose *i'* on the gas-supply cock, by a weighted arm, *j'*, as shown. Of course, the weight *j'* may be replaced by a spring. A slotted plate, *m*, is pivoted to disk *i*, which is engaged by a pin, *j''*, on pawl *j*, and which serves to control the motion of the pawl. 65

The operation of the parts is as follows: The gas being turned off, the parts are in the position shown in Fig. 3—that is to say, (the rods *e* being contracted) the pawl *j* is out of engagement with nose *i'*. If the cock is now revolved 70 to turn on the gas, the disk *i* will be revolved with it to bring the nose *i'* down into the position shown in Fig. 1. The gas being ignited, the rods *e* will expand, and by moving levers *g* *h* will cause the pawl *j* to move downward 75 and to engage nose *i'*, as shown in Fig. 2. If the gas is now turned off in the proper manner, the disk *i* will be brought back into its normal position, (shown in Fig. 1,) and the pawl *j* will also be brought, after some time, 80 into its normal condition by the contraction of rods *e*; but if the burner should be extinguished accidentally without turning off the cock the rods *e* upon contracting will cause the pawl *j* to gradually move upward, carrying, by nose 85 *i'*, the disk *i* with it, and thus closing the cock and shutting off the further supply of gas. To disengage the pawl from the disk after the cock has been closed, the nose *i'* is brought somewhat above the horizontal line, Fig. 3; or, in other 90 words, it is inclined to the direction of the movement of the pawl. In this way the pawl will under the effect of the contraction of rods *e* slide toward the front of nose *i'*, and eventually become disengaged therefrom. Thus the 95 parts are in position for the next opening of the gas-cock.

Fig. 5 shows the disk *i* provided with two noses instead of one. This construction has for its object to permit an engagement of the 100 pawl with the disk on a but partial heating of rods *e*.

What I claim is—

1. The combination of a gas-burner with

bracket *d*, and with a number of expandible rods, *e*, located above the burner-tip, and with the lever, controlling valve or cock, the rods *e* being pivotally connected to each other, and 5 being also pivotally connected to the bracket and to the lever, and with the weighted pawl *j*, pivotally connected to the lever, and with a disk, *i*, on the gas-controlling cock, said disk having a nose, *i'*, adapted to automatically dis- 10 engage from the pawl *j*, substantially as specified.

2. The combination of a gas-burner with a bracket, *d*, and with an expandible rod, *e*, above

the burner-tip, and with the levers *g h*, pivotally connected to such rod, and with a weighted 15 pawl, *j*, pivotally connected to lever *h*, and having a pin, *j'*, and with a disk, *i*, on the gas-supply cock, and having nose *i'*, and with the slotted plate *m* on disk *i*, the disk *i* being engaged by the pawl *j*, and the slotted plate *m* 20 being engaged by pin *j'*, substantially as specified.

PHILIPP MENGES.
